UNITED STATES PATENT OFFICE.

CHARLES BOOZE, OF BUFFALO, NEW YORK, ASSIGNOR TO M. H. BIRGE & SONS, OF SAME PLACE.

DESIGN FOR WALL-PAPER.

SPECIFICATION forming part of Design No. 23,621, dated September 4, 1894.

Application filed August 3, 1894. Serial No. 519,382. Term of patent 3½ years.

To all whom it may concern:

Be it known that I, CHARLES BOOZE, a citizen of the United States, residing at Buffalo, in the county of Erie and State of New York, have invented and produced a new and original Design for Wall-Paper, of which the following is a specification.

The design consists of a series of ornamental scrolls arranged to form ornamental panels with vase-like ornaments filled with flowers and leaves placed in said panels and festoons of flowers and leaves connecting said ornamental scrolls as represented in the accompanying drawing.

15 The border or upper portion of the design is formed of vase-like ornaments filled with flowers and leaves, with ornamental scrolls

diverging from said vase-like ornaments and connected by festoons of flowers and leaves, and above said festoons of flowers and leaves are placed open wreaths of flowers and leaves, the ends of which are connected by ornamental scrolls as shown in the drawing.

What I claim is—

1. The design for wall paper herein shown and described.
2. In the design for wall paper, the border herein shown and described.

Witness my hand this 31st day of July, 1894.

CHARLES BOOZE.
